UNITED STATES PATENT OFFICE

ALBERT F. CRAVER, OF LAKEWOOD, OHIO, ASSIGNOR TO THE CLEVELAND HEATER COMPANY, OF CLEVELAND, OHIO, A CORPORATION OF OHIO

WATER HEATER BAFFLE

Application filed January 5, 1931. Serial No. 506,554.

This invention relates to heating appliances and in particular baffling devices for use in connection therewith adapted to be located in the path of the heated gases from a source of heat for the purpose of effecting an efficient transfer of heat from one medium to another.

My invention is particularly adapted for use in connection with internal fired water heaters of the type employing a flue which runs through the storage vessel of the heater by means of which the heat generated by a gas burner is transferred to the liquid contents of the container. It has for its object the provision of a baffle for the heated products of combustion of a gas burner which is adapted to effect a more efficient transfer of heat to the liquid contents of the container and at the same time is designed so as to be inexpensive to manufacture and easy to install and constructed so as to greatly increase the efficiency of the heater without slowing down the velocity of the gases being vented to the point where incomplete combustion might take place.

With these and other objects in view, the invention consists in the novel construction, arrangement and combination of parts, hereinafter described, illustrated in some of its embodiments in the accompanying drawing and particularly pointed out in the appended claims.

In the drawing, Figure 1 is a sectional view showing my improved baffle in combination with an internal fired water heater.

Figure 2 is an enlarged side view of one of the baffle elements.

Figure 3 is an end view of the baffle elements.

Figure 4 is a side view showing the construction of the end portions of the baffle.

Figure 5 is a side view of the upper portion of the top baffle member.

Figure 6 is an end view of the top baffle member.

The heater shown in the drawing comprises a water storage tank or container 1 with the lower portion 13 extended below the bottom of the tank so as to form a combustion space 5 for the reception of the burner

11. This burner is provided with a central portion 4 that is adapted to function as an independently controlled pilot light. The gas supply to the main burner 11 is controlled by the valve 6, and the gas supply of the pilot 4 is controlled by a valve 7. Both of these valves are adapted to be placed into communication with a source of gas supply which may be connected to the inlet side of the body of the valve 6.

A passageway or flue 3 communicates with the combustion space 5 and extends longitudinally through the heater tank 1 terminating at the top thereof where it is adapted to be connected to a chimney by means of a suitable vent pipe. The upper portion of the tank is provided with a pair of tapped openings one of which is shown in Figure 1 and which are adapted for the reception of union fittings such as 2 whereby the cold water inlet and the hot water outlet of the heater are connected to the cold water supply line and to the hot water piping system.

In order to effect a more efficient transfer of heat in the flue 3 to the contents of the tank 1, I have devised and use an improved baffle which is preferably formed from cast iron and is made in sections so that it may be used with heaters of various lengths without requiring any change in the construction of the baffles other than that of adding or taking of additional baffle elements. The individual baffles 8 are formed with a helical surface as would result from twisting a flat strip of material and at their upper ends 85 have spacer fins 10 and notched or hooked portions 12 by means of which the adjacent baffle elements are secured to each other. The upper baffle is provided with projections or extending portions 9 which are adapted to 90 engage the upper portion of the tank for the purpose of supporting the other baffle members secured to it in position in the flue or passageway 3.

A single pattern is used in making the 95 molds for the baffle elements. This pattern is substantially the same as the baffle shown in Figure 2. When it is desired to cast the end baffle members a rectangular rod is fitted in the hooked portions 12 of the pattern so 100

that one end of the pattern would look like the baffle end portions shown in Figures 5 and 6, and the element cast from such a pattern would correspond to the upper element shown in Figure 1. By this expedient all of the baffle elements may be cast from a single pattern.

In the operation of the heater, the heated gases from the combustion space 5 flow through the flue or passageway 3 and by reason of my improved baffle are directed and thrown against the sides of the passageway and their length of travel is considerably increased so that by reason of these two factors a more efficient transfer of heat is effected, thereby increasing the over-all efficiency of the heater and effecting a marked savings in the amount of gas consumed. In addition to the effects noted, a considerable portion of the heat absorbed by the baffles is directly conducted to the sides of the flue and then transferred to the water in the tank 1. In addition to these advantages it is apparent that this baffle may be used on heaters of different lengths by merely changing the number baffle elements as required. When the baffle elements are in position in the flue 3 it is impossible to disengage them from each other as they must be laterally displaced in order to effect such disengagement and they are fitted in the flue so that it is impossible to make such displacement.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

Having thus described my invention, what I claim is:—

1. A baffle for a heating appliance comprising a plurality of detachably and vertically arranged interlocking baffle elements of cast metal, the upper baffle element of which is provided with a supporting cross bar at one end and hooks at the other end and the lower baffles of which are provided with hooks at their ends for detachable engagement with each other and with said first mentioned element.

2. A baffle for water heaters comprising a plurality of detachably and vertically arranged interlocking baffle plates formed with notched ends whereby the engagement between adjacent baffles is effected; the uppermost baffle having a laterally extending rod formed in the notched portions of one end thereof for the purpose of supporting the baffle in the heater.

3. A vertically arranged baffle for a heating appliance comprising a plurality of similarly formed detachably interlocked members, said members being provided with end

hooks for suspending one member from the other and having laterally extending fins adapted to contact with the corresponding fins of the adjacent element.

4. A vertically arranged baffle for a heating appliance comprising a plurality of detachably interlocked duplicate members of helical form, said members being provided with end hooks for suspending one member from the other and having laterally extending fins adapted to contact with the corresponding fins of the adjacent element.

In testimony whereof I affix my signature.

ALBERT F. CRAVER.
